CLAIM

(57) The ornamental design for a tire tread, as shown and described.

DESCRIPTION

FIG. 1 is a perspective view of the tire tread showing our new design;

FIG. 2 is a front view thereof;

FIG. 3 is a rear view thereof;

FIG. 4 is a left side view thereof;

FIG. 5 is a right side view thereof;

FIG. 6 is a front view showing the location of cross-sectional views shown in FIGS. 7; and,

FIG. 7 is a cross-sectional view taken along line 7-7 in FIG. 6.

The broken lines in the drawings depict portions of the tire tread that form no part of the claimed design.
